HIS ATTORNEYS

UNITED STATES PATENT OFFICE

ERNEST G. JOHNSON, OF CHICAGO, ILLINOIS

TOOTHBRAUSH

Application filed March 4, 1931. Serial No. 520,110.

This invention relates to certain novel improvements in tooth brushes, and has for its principal object the provision of an improved construction of this character which will be highly efficient in use and economical in manufacture.

The salient object of this invention is to provide a tooth brush which will effectively massage the gums during the tooth brushing operation.

Another object of the invention is to provide a brush in which a plurality of resilient caps are provided, each of these caps having a recess therein so that when the caps are rubbed over the teeth and gums partial vacuums will be produced by the depressions in the resilient caps thereby stimulating and massaging the gums.

Other objects will appear hereinafter.

50 The invention consists in the novel combination and arrangement of parts to be hereinafter described and claimed.

The invention will be best understood by reference to the accompanying drawings, 55 showing the preferred form of construction and in which:

Fig. 1 is a plan view of a preferred form of construction of the invention;

Fig. 2 is a sectional detail view on an enlarged scale, on the line 2—2 in Fig. 1; and

Fig. 3 is a sectional detail view on the line 3—3 in Fig. 2.

Referring to the drawings wherein a preferred embodiment of the invention is depicted my improved brush is generically indicated at 10 and includes a handle 11 of conventional design with which is integral a head 12. Formed in the head 12, on one side thereof, is a recess 13 around the upper side of which extends a flange or head 14.

Mounted in the recess 13 is a bristle bearing base 15 with which are formed integrally a plurality of resilient cups 16 which may be of any suitable resilient material such, for example, as rubber, and in each of these cups is a cavity 17 which, in the present instance, is substantially cone-shaped, although these cavities or recesses 17 may be of other shapes within the purview of the invention.

50 The base 15 and cups 16 are held in posi-

tion by a retaining plate 18 which is held in position by the head 14, the plate 18 being preferably, though not necessarily, of a light metal such, for example, as aluminum and having openings 19 therein through which the cups 16 may be extended.

In use the resilient cups will be compressed by the pressure exerted thereon during the operation of brushing the teeth and as the cups are compressed against the gums partial vacuums will be formed in the recesses or cavities 17 which will cause a pulling action to be exerted on the gum tissues, thereby effectively massaging and stimulating the gums and promoting the circulation therein and healthfulness thereof, without injuring the gums or causing pain, while, manifestly, the cups will permit a dentifrice to be disposed thereon so that the teeth may be brushed and cleaned.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claim.

Having thus described my invention what I claim as new and desire to protect by Letters Patent is:

60 A tooth brush comprising a handle, a head having a recess therein, a head extending around said recess, a base in the recess, a plurality of resilient cup elements mounted in said base, each of said cup elements having a cavity therein, and a retaining plate disposed over said base and held thereon by said head, said plate having openings therein through which said cup elements are extended.

In testimony whereof I affix my signature.

ERNEST G. JOHNSON.
